(57) **CLAIM**

The ornamental design for a transport tube holder assembly with internal and external ribs, as shown and described.

DESCRIPTION

FIG. 1 is a frontwardly directed perspective view of a transport tube holder assembly with internal and external ribs in accordance with an embodiment of the present invention.

FIG. 2 is a rearwardly directed perspective view of the transport tube holder assembly of FIG. 1 in accordance with an embodiment of the present invention.

FIG. 3 is a top view of the transport tube holder assembly of FIG. 1 in accordance with an embodiment of the present invention.

FIG. 4 is a left side view of the transport tube holder assembly of FIG. 1 in accordance with an embodiment of the present invention.

FIG. 5 is a rear view of the transport tube holder assembly of FIG. 1 in accordance with an embodiment of the present invention.

FIG. 6 is a front view of the transport tube holder assembly of FIG. 1 in accordance with an embodiment of the present invention.

FIG. 7 is a right side view of the transport tube holder assembly of FIG. 1 in accordance with an embodiment of the present invention.

FIG. 8 is a bottom view of the transport tube holder assembly of FIG. 1 in accordance with an embodiment of the present invention.

FIG. 9 is a cross-sectional view of the transport tube holder assembly of FIG. 1 taken along line 9—9 in accordance with an embodiment of the present invention.

FIG. 10 is a close-up sectional view of the cross-sectional view of FIG. 9 taken along section 10 in accordance with an embodiment of the present invention.

FIG. 11 is a frontwardly directed perspective view of a second embodiment of the transport tube holder assembly in which the design of the first embodiment is shown broken away in order to indicate that a specific width and number of elements

disposed between the claimed regions of the assembly form no part of the claimed design; and,

FIG. 12 is a frontwardly directed perspective view of a third embodiment of the transport tube holder assembly in which the design of the first embodiment is shown broken away in order to indicate that a specific length and number of elements disposed between the claimed regions of the assembly form no part of the claimed design.

The broken lines shown in FIGS. 1-2, 4-7, and 11-12 are provided for the purpose of showing environment only, and form no portion of the claimed design.
